KITE ATTACHMENT, CLIP, AUXILIARY RETAINER, AND RELEASE MECHANISM

Joseph Wolf, Brooklyn, N. Y.

Application December 7, 1948, Serial No. 64,008

10 Claims. (Cl. 244—155)

1

The present invention relates to a device for retaining individual or a plurality of varied attachments, supported on a kite string, while the kite is in flight, and positive means for rapidly releasing these attachments, such means being controllable by the operator on the ground.

In flying kites of various types, it has been found that the interest is considerably enhanced by having attached to the string of the kite, a number of objects, such as miniature gliders, parachute-borne figures, bird models and the like, which may be released, while the kite is in the air, the various objects floating downward and returning to the ground.

While various devices of this general type have been available, the method of supporting the attachments on the kite string, and the method of releasing them therefrom have not been generally satisfactory, due primarily to the fact that the operator could not control and regulate the time of release, while the kite was in flight.

In devices of this character, it is essential that all of the attachments, carried on the kite string, be as light as practicable, so as not to retard the raising of the kite, or affect its maneuverability. It is further essential that the clip or support used for retaining the various attachments be light, and that the lock or latching mechanism used to hold the objects in the air be positive, so that the objects will not be released, until the operator is ready to release them.

It is therefore essential that a simple, positive release, controllable from the ground, be provided in order to enable the operator to release the various attachments, at will, when the kite has reached a predetermined altitude, or when the objects are over a selected area.

One object of my invention is to provide a support for individual attachments or a variety of kite attachments, which is positive in its action, and by means of which the various objects carried can be readily released under the control of the operator.

A further object is to provide a simple retaining device or clip, so that comparatively unskilled youngsters can readily attach the various objects thereto, and operate the releasing mechanism without difficulty.

A further object is to provide a releasing mechanism which is light, relatively fool-proof, and will withstand the strains encountered while the kite is in the air, without distortion.

A further object is to provide a variety of kite attachments which are simple, can be produced at a low cost and are light in weight.

Another object is to provide a releasing device which is light, rugged and will climb the kite string, and pass any knots or other obstructions, which may be formed thereon, by means of the air pressure behind it, with a minimum of friction and without injury to the kite string.

The accompanying drawings, illustrative of one embodiment and various modifications of my invention together with the description of their construction and the method of operation thereof, will serve to clarify further objects and advantages of my invention.

In the drawings:

Fig. 1 represents an isometric view of the kite attached to a kite string, and a side elevation of a quick-release clip, with an auxiliary retainer attached thereto, also a miniature glider, a figure of a parachutist, with a rolled parachute fitted thereto, and a plurality of simulated birds, releasably mounted on the auxiliary retainer arm.

Fig. 2 represents a view of the kite in flight, similar to Fig. 1, with the release disc in engagement with the releasing mechanism of the clip latch, both the clip and the auxiliary retainer being open, with the various objects floating freely toward the ground.

Fig. 3 is a rear elevation of the figure of a parachutist, attached to a parachute, with the parachute open.

Fig. 4 represents side elevation of the kite attachment clip in the closed position.

Fig. 5 is a side elevation of the clip with the central latch moved to the open position.

Fig. 6 is a vertical section thru the clip and latch taken at 6—6, Fig. 4, showing the depression formed in one wall of the clip housing for arresting the latch in the closed position.

Fig. 7 is a vertical section, taken at 7—7, Fig. 4, showing the rivet connecting the two side walls of clip housing, and the slots in the latch, limiting the lateral movement of the latch.

Fig. 8 is a front elevation of the attachment clip and the clip latch, showing the opening in the flange, which fits over the kite string.

Fig. 9 represents a front elevation of the release disc assembly.

Fig. 10 is a vertical section thru the release disc and the plate and bracket supporting it, taken at 10—10, Fig. 9.

Fig. 11 represents a front elevation of the release disc hub bracket, taken at 11—11, Fig. 10.

Fig. 12 is an isometric drawing of the auxiliary retainer loop bracket, which supports the pivoted support element of the auxiliary retainer, shown

in Figs. 1 and 19, showing the end of the support rod in the loop of the bracket.

Fig. 13 is a plan view of the miniature glider, supported by the auxiliary retainer in Fig. 1.

Fig. 14 is a side elevation of the miniature glider of Fig. 13, showing the channel bracket, used for supporting it on the auxiliary retainer.

Fig. 15 is a rear elevation of the figure of the parachutist with the parachute rolled up and supported inside the mounting bracket, showing the weight attached to the figure.

Fig. 16 is a side elevation of the figure of the parachutist of Fig. 15, showing the mounting bracket and the method of supporting the rolled parachute within the bracket, also the method of attaching the weight to the figure.

Fig. 17 is a plan view of the simulated birds, shown in Figs. 1 and 2.

Fig. 18 is a side elevation of a stack of simulated birds, shown in Fig. 17.

Fig. 19 is a side elevation of the auxiliary retainer assembly, attached to the clip.

Fig. 20 represents a side elevation of the attachment clip assembly, of Fig. 1, mounted on the kite string, with the miniature glider bracket supported directly on the lugs of the clip latch.

Fig. 21 is a plan view of the hooked end of the auxiliary retainer anchor.

As indicated in Figs. 1 and 2, the attachments may be mounted on a quick-release clip, and an auxiliary retainer, the clip being connected to a kite string, one end of which is attached to the front end of a conventional type of kite or box-kite, which is raised by the wind in the usual manner.

A clip which is fitted with a quick-release latch may be attached to the kite string by looping the ends of string sections thru openings formed at both ends of the clip housing, or by any other suitable means.

An auxiliary retainer, formed of aluminum wire or other suitable material which is held on the kite string by an anchor section, one end of which has a series of coils formed thereon, the coils being slidably supported by the kite string, with the opposite hooked end pivotally attached to the clip housing may be mounted on the kite string, adjacent the clip.

A loop formed at one end of the lower support section of the auxiliary retainer may be fitted into the coils in the anchor bracket, thus hingedly connecting the attachment support section of the retainer to the anchor, the free end of the support fitting into the looped end of a quick-release bracket, pivotally attached to the clip housing, thru an opening formed in the front end of the clip housing.

Various attachments in the form of miniature gliders, figures of various types, and simulated birds may be supported by the releasing clip-latch, the auxiliary retainer, or both, as indicated in Figs. 1 and 20.

The larger attachments, such as miniature gliders or large figures, may be supported on the clip or the auxiliary retainer by means of U-shaped brackets, the upper end of the arms of which have openings formed therein, to slidably fit over the wire support of the auxiliary retainer, or both lugs of the quick-release clip latch, the spacing of the arms of the bracket corresponding to the spacing of the slots in the clip housing.

The latching element of the quick-release clip may be slidably supported in the U-shaped housing of the clip, with a release flange, located at an angle to the latch extension, formed integral

with the latch at the front end thereof, an opening in the angular flange fitting over the kite string to slidably support the flange on the kite string.

5 The forward edge of the angular flange, and the outer edge of the horizontal extension of the latch are located in substantial alignment with one another, to enable the plate of the release disc to engage both surfaces simultaneously, in order 10 to open the latch.

A release disc consisting of a thin card-board disc, or other suitable material, may be mounted between a plate and a mounting bracket, the flanged arms of which may be attached by riveting or other suitable means to the central portion 15 of the disc.

The hub at the center of the release disc plate, similarly the hub formed in the outer wall of the bracket, may be turned inward around the opening formed at the center, the open end of the rim of the opening being flanged outward, the corners being rounded to present a smooth surface to the kite string, regardless of the altitude and position of the disc, to avoid cutting or tearing the string, and to reduce to a minimum, the frictional resistance, encountered by the disc, when it is slid along the kite string. The openings in the plate and bracket hubs are made large enough to clear any knots which may be formed in the kite string.

30 While the kite is in normal flight, the release disc may be held back by the operator, or supported on the string near the ball supply end, which is controlled by the operator, the ball being left on the ground.

When the kite reaches an altitude at which the operator desires to release the various attachments, the release disc may be freed by the operator, the disc being picked up by the wind and 40 rapidly moved along the kite string, until the hub plate reaches the release arm and flange of the latch.

When the hub plate engages the release arm and the flange of the latch, the latch is slid along 45 the clip housing, the lugs formed at the lower end of the latch being moved free of the slots in the side walls of the clip housing, thus releasing the attachments, such as the miniature glider, shown in Fig. 20, the bracket of which is mounted 50 directly on the lugs of the latch, and simultaneously releasing the looped end of the pivoted bracket which fits over the rear lug, thus releasing the lower arm of the auxiliary retainer, and releasing the attachments slidably mounted on the arm, the various attachments floating downward toward the ground, as indicated in Fig. 2.

It will be understood that the foregoing general description of the construction and operation of the kite attachments, clip, auxiliary retainer and 60 release mechanism, as well as the following detailed description thereof, are intended as explanatory of the invention and not restrictive thereof.

In the drawings, the same reference numerals 65 designate the same parts throughout the various views except where otherwise indicated.

In the kite assembly, shown in Fig. 1, a kite 10 is attached to one end of a long string 11, the opposite end of which is fed from a ball or reel (not shown). A clip 12 comprising a U-shaped housing 13, in which a latch 14 is slidably fitted, may be attached to the kite string by looping the end 15 of a section of the kite string thru an opening formed in the upper end of the rear of the housing, the end of the rear portion 16 of the string

being attached in a similar manner thru a similar opening 17, formed at the opposite end of the clip housing.

An auxiliary retainer 18, formed of an aluminum alloy wire or other suitable material, may be demountably attached to one end of the clip housing, the hooked end 19 of the upper retainer anchor 20, being pivotally fitted into the rear opening 15 in the clip housing, as indicated in detail in Fig. 19, with a series of coils 21, formed at the opposite end of the auxiliary retainer anchor, slidably fitted over the forward portion of the kite string, the point of attachment to the kite string being far enough away from the kite to avoid any possibility of interference with the movement of the tail 22, attached to the lower end of the kite.

An extension leg 23 of the hooked end of the anchor bar formed substantially parallel to the long anchor spacer bar 24 of the anchor, which connects the hooked end with the multiple coils at the opposite end, is spaced from the anchor bar, a distance slightly greater than the width across the channel side walls 25 and 26, Figs. 6 and 7, and is made long enough to avoid accidental removal of the hooked end 19 of the anchor from the housing.

In mounting the anchor 20 on the kite string, the open end of the end coil of the multiple coils, at one end of the anchor, is fitted over the kite string, and the adjacent coils looped over the kite string until the coils slidably fit over the kite string.

The extension leg 24 is then fitted into the opening 15, at the rear end of the housing 13, with the spacer bar located above the upper connecting wall 27 of the housing, after which the anchor is rotated into a position in which the spacer bar is substantially parallel to the side walls of the housing, the hooked end supporting the anchor on the clip housing.

The auxiliary retainer may be removed from the kite string and clip, when the wind is not sufficiently strong to carry a large number of attachments, by threading the multiple coils 21 over the kite string and detaching the hooked end 19 of the anchor from the clip housing in the manner above described.

The substantially L-shaped attachment support section 30, of the auxiliary retainer may be attached to the anchor by means of an eye 31, formed at the upper end of the vertical arm 32, of the support section, which is linked to the multiple coils 21 formed at the rear end of the anchor, with the open end of the lower support rod 33, of the auxiliary retainer support, fitted into the looped end 34, of a loop bracket 35, the upper end of which may be pivotally attached to the clip housing by means of the hooked end 36 of the bracket, Fig. 12, which is fitted thru the forward opening 17, formed in the clip housing, thus pivotally supporting the bracket in the housing, the loop 34, formed at the free end of the bracket being fitted over the rear lug 37, formed at the lower end of the clip latch, Fig. 4, to hold the auxiliary retainer support in the closed position, substantially parallel to the kite string, as indicated in Fig. 1.

The extension leg 40 of the pivoted loop bracket formed substantially parallel to the main bracket arm 41, is spaced from the arm a distance greater than the width across the channel side walls 25 and 26, Figs. 6 and 7, and is made long enough to avoid accidental removal of the hooked end of the bracket from the housing. In mounting the

70 75

bracket 35 on the clip housing, the extension leg 40 is fitted into the opening 17 at the forward end of the housing, with the bracket arm 41 located above the upper connecting wall 27 of the housing, after which the bracket is rotated into a position, in which the arm is substantially parallel to the side walls of the housing, the hooked end pivotally supporting the bracket in the housing.

A plurality of attachments in the form of a miniature glider 42, a figure of a parachutist 43, carrying a parachute 44, a plurality of simulated birds 45, or other suitable objects or figures, may be mounted on the clip or the auxiliary retainer after the kite is raised to a suitable level.

The larger objects, such as the miniature glider, or the figure of the parachutist may be mounted on the clip latch or the auxiliary retainer support by means of brackets 46 and 47, the substantially vertical arms 48 and 49 of each of which have openings 50 and 51 formed at the upper end thereof, Figs. 14 and 15, the openings in the bracket arms fitting over the lugs in the latch or over the support arm of the auxiliary retainer support section, as indicated in Figs. 1 and 20, the actual point of mounting depending upon the number of attachments used, and the order in which the operator desires to release the various attachments. The lower connecting wall 52 of the bracket may be attached to the miniature glider fuselage 53 by a plurality of screws 54, or by other suitable means of attachment. The rear vertical arm 48 of the bracket 46, supporting the miniature glider is made longer than the front arm, and the openings 50 and 51 in the arms located in such a position, with relation to the miniature glider, that the glider assumes a substantially horizontal position with relation to the ground when the kite string assumes its normal angle, while the kite is in flight. Thus the fuselage 53 of the miniature glider is supported in a substantially horizontal position in Fig. 1.

When the miniature glider is mounted directly on the lugs of the clip, as indicated in Fig. 20, the short arm 49 of the bracket is located in the position towards the kite, thus throwing the fuselage 53 of the glider into an acute angle with relation to the kite string, in order to enable the top of the rudder 55 of the glider to clear the outer circumference of the release disc 56, when the release disc assembly is moved along the kite string to open the latch of the clip, and release the attachments in a manner hereinafter explained.

In the assembly shown in Fig. 1, the figure of the parachutist 43 is slidably mounted on the support rod 33 of the auxiliary retainer by means of a bracket 47, similar to the one used to support the glider. As the rear vertical arm 49 is shorter than the forward vertical arm of the bracket in the position shown, the figure assumes an angular position, with relation to the kite string in its normal position, and also in relation to the ground, as indicated in Fig. 1.

The clip as indicated in Figs. 4 and 5, comprises a housing 13, formed of sheet aluminum alloy or other suitable material, the cross section of the channel housing being U-shaped, as indicated in Figs. 6 and 7, with a latch 14, slidably fitted between the channel side walls 25 and 26 of the housing. A plurality of tubular rivets 58 may be used to locate the two channel side walls of the housing, the rivets spacing the inner surfaces of the side walls, a distance slightly greater than the thickness of the latch 14, to enable the latch to be slid between the side walls with-

out interference, slots 59 and 60, formed in the body 61 of the latch, fitting over the body of the rivets to limit the lateral movement of the latch in both directions, as indicated in Fig. 4. In the closed position of the latch, shown in Fig. 4, the two lugs 37 and 62, formed at the bottom of the latch, formed parallel with the bottom of the side walls of the clip housing are in substantial alignment with two U-shaped slots 63 and 64, formed at the lower end of the channel side walls of the clip housing.

A depression 65 may be formed in one side wall 26 of the housing, the outer hemispherical surface formed by the depression, pressing the body of the latch against the opposite side wall 25, while the latch is moved into the closed position, the pressure of the hemispherical surface against the latch acting as a check to prevent the accidental opening of the latch, when it is in the closed position, shown in Fig. 4.

At the front end of the latch extension 66, a flange 67 formed by folding the outer end of the latch extension to a position angularly disposed to the axis of the latch body, and a folded contact end 68, formed by twisting the intermediate section of the latch extension to a plane substantially perpendicular to the body of the latch, are formed integral with the body of the latch. An opening 69 formed in the upper portion of the flange 67 may be slidably fitted over the kite string, as indicated in Figs. 1, 2 and 20.

The outer edge of the flange 67 and the edge of the contact arm 68 of the latch are located in a position substantially perpendicular to the axis of the latch, to enable the release disc plate to engage both surfaces simultaneously, in the releasing position as indicated in Fig. 2.

The simulated birds 45, may be slidably mounted on the lower support rod 33, of the auxiliary retainer, as indicated in Fig. 1, or mounted on one of the lugs 37 and 62 of the clip latch, by means of an opening 70 formed in the tail of the bird body, Fig. 17. The birds may be released from the clip or the auxiliary retainer in the same manner as the other attachments hereinbefore described.

In order to release the various attachments from the clip and the auxiliary retainer, a release disc assembly 74, shown in detail in Figs. 9 and 10, may be slid along the kite string, the wind pressure against the body of the disc 56 carrying the disc assembly diagonally upward along the kite string, until the plate 76, mounted at substantially the center of the forward face of the disc engages the flange 67 and the contact end 68 of the latch, thus sliding the latch along the clip housing from the closed position, shown in Fig. 4, to the open position, shown in Fig. 5, with the lugs out of alignment with the slots 63 and 64 in the side walls of the clip housing.

The release disc assembly 74, shown in detail in Figs. 9 and 10, constitutes essentially a substantially circular disc 56, with an opening 77 formed at the center thereof. A substantially U-shaped bracket 78, the lower end of the legs 79 of which are flanged to fit the face of the disc, may be attached to the disc by means of tubular rivets 80, which connect the forward plate 76, the disc, and the lower flanges of the disc bracket.

The hub 81 formed in the rear wall of the disc bracket, Fig. 11, is larger, in diameter, than the width of the bracket legs, an opening 82 being provided at the center of the hub, with the rim 83 of the opening flanged inward, the open end of the rim circumference being flanged outward, all

corners being rounded, to provide a smooth surface in engagement with the kite string, to reduce frictional resistance against the kite string to a minimum, in order to avoid cutting or tearing the string, and to facilitate movement over knots formed in the kite string, when the release disc is slid along, toward the clip latch controls.

The plate 76, located at the forward face of the release disc has a similar opening 84 formed thru the center thereof, with the rim 85 of the opening flanged inward, the open end of the rim circumference being flanged outward, all corners being rounded, in the same manner as that of the opening formed in the hub of the bracket 78, and previously described.

The openings 84 in the release disc plate and 82 in the hub of the bracket 78 are made considerably larger than the diameter of the kite string in order to enable the disc assembly to slide along the kite string and pass over any knots formed in the string, or knotted joints 97 formed when sections of the string are tied together, as shown in Figs. 1, 2 and 20.

A weight 86 may be attached to the rear end of the body of the figure 43 of the parachutist by means of rivets 87, or other suitable means of attachment, as indicated in Figs. 3 and 15, the weight moving the figure into a substantially vertical position, thus facilitating the removal of the parachute from the bracket attached to the figure, when the bracket and figure are released from the auxiliary retainer support rod, and maintaining the figure in the substantially vertical position, while it is floating downward, with the parachute open, as indicated at Fig. 3.

The figure may be attached to one arm of the bracket 47 by means of a plurality of hollow rivets 88, or by other suitable means of attachment.

The parachute 44, Fig. 3, made of thin paper, or other suitable materials, may be attached to the lower connecting wall 52 of the bracket 47, attached to the figure of the parachutist by means of a plurality of angular strings 91. The lower end of the strings may pass thru an opening formed in the lower connecting wall 52 of the bracket, a knot 92 formed at the free end of the strings preventing the accidental removal of the strings thru the opening. Other means of attachment of the parachute, known to the art may however be used.

The method of assembly of the various units to the kite string and the method of operation are essentially as follows:

Before the end of the kite string is attached to the guy strings 95, of the kite, the release disc assembly 74 is slidably mounted on the kite string by threading the free end of the kite string thru the openings 82 and 84 in the release disc bracket and plate respectively, the kite string 60 being fed from a ball or reel, which rests on the ground, or is held by the operator, in the conventional manner.

The end 96 of the rear section 16 of the kite string is then slipped thru the opening 69, formed in the flange 67, at the forward end of the latch, which is slidably assembled in the clip housing, as indicated in Fig. 4, after which the kite string end is slipped thru the opening 17 formed in the forward end of the clip housing and tied into a knot, to secure it to the housing. One end of a shirt length 98 of the kite string, approximately two feet long may then be fed thru the opening 15 in the rear end of the clip housing and knotted to secure it to the clip housing, the other end 75 of the string length 98, being left free.

In this manner an assembly suitable for mounting an individual attachment or attachments, such as a miniature glider, directly on the lugs of the latch, as indicated in Fig. 20 is available for attachment to the free end of the kite string 11 attached to the kite.

A kite string 11, from another ball, may then be attached to the guy strings 95 of the conventional type of kite 10, as indicated in Fig. 1. The kite is then raised, in the conventional manner to a convenient height, at which it is stabilized in flight, after which the free end of the kite string 11, is attached by knotting 97, or other suitable means to the free end of the short length 98 of kite string, attached to the clip housing.

This provides the kite and clip assembly, shown in Fig. 20.

One or more attachments, such as the miniature glider 42, the figure of the parachutist 43, the simulated birds 45, may be mounted directly on the lugs 37 and 62 of the latch, by passing the lugs thru the openings 50 and 51, formed in the bracket 46 or 47, attached to the miniature glider or the figure of the parachutist, in the manner previously described, or the opening 70 formed in the tail of the simulated birds 45 or other simple figure may be slipped over one of the lugs 37 or 62 of the clip latch, when the clip is in the open position, shown in Fig. 5. The clip latch is then moved into the closed position, shown in Fig. 4, thus locking the attachment in place.

While the release disc assembly 14 and the ball of string are on the ground, the operator feeds the rear section 16, of the kite string thru his hand, thus allowing the kite to rise to any height to which the wind will carry it, the clip and the attachments mounted on it being carried up with the kite string.

The operator may then grip a portion of the kite string, behind the release disc assembly, the ball of string being left on the ground, after which the operator continues to feed the kite string thru his hand, allowing the release disc assembly, the plate 76 and bracket 78 of which are slidably mounted on the kite string, to be carried upward by the kite for a short distance, after which the wind pressure behind the release disc, rapidly elevates the disc assembly along the kite string. The wind continues to move the release disc assembly until the plate 76 at the front of the release disc engages the free end of the flange 67, and the contact arm 68, of the clip latch, the momentum of the release disc assembly and the wind pressure combining to move the clip latch from the closed position, shown in Fig. 4 to the open position, shown in Fig. 5, thereby releasing the attachments, and allowing them to fall freely toward the ground, as indicated in Fig. 2.

Where the wind velocity is sufficiently strong to support additional attachments, the upper anchor 20 of the auxiliary retainer 18, may be attached to the opening 15 at the rear end of the clip housing, and the coils 21 formed at the rear end of the anchor, threaded over the kite string, to the position shown in Fig. 1, while the kite is in flight, without disturbing the clip assembly, which is already attached to the kite string.

By mounting various attachments, such as the miniature glider, the figure of the parachutist, and the simulated birds on the lower rod, of the support section 30 of the auxiliary retainer, a large number of attachments may be mounted on the kite string.

The free end of the lower support bar may then

be slipped into the loop 34 of the loop bracket, which is fitted over the rear lug 37 of the clip latch, the latch being manually moved into closed position, as indicated in Fig. 1.

The kite string, with the plurality of attachments mounted on the auxiliary retainer, is then fed by the operator, until the kite reaches a suitable height, after which the release disc assembly 14 is freed by the operator, and the wind pressure carries it upward along the kite string until the plate reaches the flange and control arm of the clip latch, in the manner previously described, the continued movement of the release disc assembly moving the clip latch from the closed to the open position, thus allowing the loop 34 of the loop bracket to slip off the lug, thereby allowing the open end of the lower support rod of the auxiliary retainer support to drop, the various attachments being progressively released, as indicated in Fig. 2.

The number of attachments mounted on the kite string would depend upon the size of the kite, the weight of the various attachments, the number lugs on the releasing clip, the size and type of the auxiliary retainer used, and the velocity of the wind.

Ordinarily, in order to offer a minimum restraint to the altitude of the kite in flight, one clip and one auxiliary retainer would be used, with three or four attachments mounted on them.

Where the kite is flown at a time when the wind is not particularly strong, only one clip would be used with the attachment or the attachment bracket mounted directly on the lugs of the latch, as indicated in Fig. 20, the auxiliary retainer being removed or omitted to reduce the weight carried by the kite.

It will, accordingly, be appreciated that the kite attachments, clip, auxiliary retainer and release mechanism, herein described, has new and useful constructional and operational features offering distinct advantages over existing types of kite attachment supports. It will, moreover, be apparent to those skilled in the art that the foregoing description of the various modifications of the construction is illustrative, and that numerous changes can be made therein, without departing from the essentials of the invention which is, rather defined by the appended claims.

What I claim as new and desire to secure by Letters Patent is:

1. A device for detachably supporting a plurality of objects on a kite string, attached to a kite, comprising a clip, said clip including a housing, means for attaching the housing to the kite string, a latch slidably fitted within said housing, means formed integral with said latch for detachably supporting one of said objects, means formed integral with the latch for moving the latch from the closed to the open position, an auxiliary retainer, said retainer comprising an anchor bracket pivotally attached to one end of the clip housing, means for slidably supporting said anchor bracket on the kite string, an attachment support pivotally attached to said anchor bracket, said support being adapted for slidably holding a plurality of objects, means pivotally attached to the clip housing for releasably supporting the open end of the attachment support on the support means of the clip latch, and means formed integral with one end of the clip latch for sliding the latch from the closed to the open position, the objects slidably mounted on said retainer support being progressively released when the latch is opened.

2. The combination with a kite and string attached thereto, of a clip, a plurality of objects adapted to gravitate toward the ground when released, said clip including a substantially U-shaped housing, means for attaching the housing to the kite string, a latch slidably fitted between the walls of said housing, a plurality of lugs formed integral with said latch for detachably supporting some of said objects, a plurality of slots formed in the walls of said housing, in substantial alignment with said lugs, in the closed position, means formed integral with said latch for moving the latch from the closed to the open position, an auxiliary retainer, said retainer comprising an anchor bracket, pivotally attached to one end of the clip housing, means for slidably supporting said anchor bracket on the kite string, an attachment support, pivotally attached to said anchor bracket, said support being adapted to slidably hold a plurality of releasable objects, a looped bracket pivotally attached to the clip housing for releasably supporting the open end of the attachment support on one of the lugs of the clip latch, and control elements formed integral with one end of the clip latch for sliding the latch from the closed to the open position, the objects slidably mounted on the retainer support being progressively released when the latch is opened.

3. In combination with a kite and a string attached thereto, a clip, a plurality of objects adapted to gravitate toward the ground when released, said clip comprising a housing of substantially U-shaped cross-section, said clip housing being attached to the kite string, a latch slidably mounted between the walls of said clip housing, means formed integral with said latch for detachably supporting a plurality of objects, control elements formed integral with said latch for sliding the latch from the closed to the open position, an auxiliary retainer, said auxiliary retainer comprising an anchor member pivotally attached to the clip body, the opposite end of said anchor member being slidably supported on the kite string, an attachment support section for slidably supporting a plurality of objects, pivotally attached to said anchor member, means pivotally attached to the clip housing for releasably supporting the open end of the support section on one of the latch lugs, a disc assembly, slidably mounted on the kite string, for engaging the control elements of the latch, said disc assembly being slidably moved along the kite string by the velocity of the wind, the latch being moved from the closed to the open position. Thereby releasing the support section of the auxiliary retainer, when the disc assembly engages the control elements of the latch, the objects falling toward the ground.

4. In combination with a kite and a string attached thereto, a clip, a plurality of releasable objects, said clip comprising a substantially U-shaped housing attached to the kite string, a latch slidably mounted between the walls of said clip housing, a plurality of lugs formed integral with said latch for detachably supporting an object which gravitates downward when released, control elements formed integral with said latch for sliding the latch from the closed to the open position, an auxiliary retainer, said auxiliary retainer comprising an anchor member, pivotally attached to the clip housing, the opposite end of said anchor member being slidably supported on the kite string, an attachment support section for slidably supporting a plurality of objects, pivotally attached to said anchor member, a looped

bracket pivotally attached to the clip housing for releasably supporting the open end of the support section on one of the latch lugs, a disc assembly, slidably mounted on the kite string, for engaging the control elements of the latch, said disc assembly being carried along the kite string by the velocity of the wind, said latch being moved from the closed to the open position, thereby releasing the support section of the auxiliary retainer, when the disc assembly engages the control elements of the latch, the objects descending toward the ground.

5. A releasing member slidably mounted on a kite string, attached to a kite, comprising a disc, a plate adjoining one face of the disc, and a substantially U-shaped bracket, said bracket having a plurality of flanges formed therein, mounted at the opposite face of said disc, means for attaching the bracket flanges and the plate to the release disc, said plate having an opening formed therein, in substantial alignment with an opening formed at the center of the disc, said plate opening being larger than the diameter of the kite string to pass knots formed in the kite string, the rim of said opening being flanged inward, with the free end of the rim circumference flanged outward, the junction corners being rounded, to facilitate sliding the disc assembly along the kite string, the outer wall of the bracket having a similar opening formed therein, the rim of said opening being flanged inward, with the free end of the rim circumference flanged outward, the junction corners being rounded, said openings being slidably mounted on the kite string to hold the disc in its correct position, with relation to the kite string, while the releasing member is angularly elevated along the kite string.

6. A figure for detachable mounting on a releasing support element of a retaining member, mounted on a kite string, attached to a kite, comprising a formed figure, a substantially U-shaped bracket attached to said figure, one arm of said bracket being longer than the other to control the angular position of the figure with relation to the kite string, each of said bracket arms having an opening formed therein, adjacent the open end thereof, said openings slidably fitting over the support element of the retaining member, attached to the kite string, and a parachute rolled into the inner portion of the U-shaped bracket, the free end of the strings attached to said parachute being attached to said bracket, said parachute opening to retard the rate of descent of said figure, when the bracket arms are released from the support element of the retaining member.

7. A figure of a parachutist for detachable mounting on a releasing support element of a retaining member mounted on a kite string, attached to a kite, comprising a figure in the form of a parachutist, a substantially U-shaped bracket attached to said figure, one arm of said bracket being longer than the other to control the angular position of the figure with relation to the kite string, each of said bracket arms having an opening formed therein adjacent the open end thereof, said openings slidably fitting over the support element of the retaining member attached to the kite string, a parachute rolled into the inner portion of the U-shaped bracket, the free end of the angular strings attached to said parachute being attached to said bracket, and a weight attached to the body of the figure, said weight accelerating the rate of falling of the figure assembly and controlling the angular posi-

tion of the figure, the parachute opening to retard the rate of falling of said figure, when the bracket arms are released from the support element of the retaining member.

8. A figure for detachable mounting on a releasing support element of a retaining member mounted on a kite string attached to a kite, comprising a formed figure, a substantially U-shaped bracket attached to said figure, each of the arms of said bracket having an opening formed adjacent the outer end thereof, said openings slidably fitting over the support element of the retaining member, attached to the kite string, a parachute rolled into the inner portion of the U-shaped bracket, the free end of the strings attached to said parachute being attached to said bracket, and a weight attached to the body of the figure, said weight controlling the angular position of the figure, the parachute opening to regulate the rate of falling of the figure, when the bracket arms are released from the support element of the retaining member.

9. A quick-release clip for detachably supporting an object which gravitates downward when released, on a kite string attached to a kite, comprising a substantially U-shaped housing, a latch slidably mounted between the walls of said housing, a plurality of lugs formed integral with said latch for detachably supporting said object, a plurality of rivets for relatively locating the side walls of the housing, said latch having a plurality of slots formed therein, the ends of said slots engaging the rivets for limiting the lateral movement of the latch in both directions, the walls of said housing having a plurality of substantially U-shaped slots formed therein, in substantial alignment with the latch lugs in the closed position, one wall of said housing having a depression formed therein, the surface of said depression, at the inner side of the wall, pressing the latch against the opposite wall to check the movement of the latch in the closed position, the walls of said housing having a plurality of openings formed therein, adjacent the ends thereof, the ends of the kite string fitting thru said openings for attaching the string to the housing, and control elements formed integral with one end of the latch for sliding the latch from the closed to the open position.

10. In combination with a kite and a string attached thereto, a quick-release clip, said clip

comprising a housing of substantially U-shaped cross-section, a latch slidably mounted between the walls of said housing, a plurality of lugs formed integral with said latch for detachably supporting a plurality of objects, control elements formed integral with said latch for sliding the latch from the closed to the open position, an auxiliary retainer, said retainer comprising an anchor member, pivotally attached to the clip housing, a plurality of coils formed at the opposite end of said anchor member being slidably mounted on the kite string, an attachment support section for slidably supporting a plurality of objects pivotally attached to said coils, a bracket pivotally attached to said housing, the free end of said bracket having a loop formed therein, said loop releasably supporting the open end of the support section on one of the latch lugs, a disc assembly slidably mounted on the kite string, said disc assembly comprising a disc having an opening formed therein, a plate attached to one face of said disc, a bracket attached to the opposite face of said disc, said plate and bracket each having an opening formed therein, substantially in alignment with the opening in the plate, the diameter of said openings being larger than the kite string to enable said disc assembly to readily pass knots in the kite string, said disc assembly being elevated along the kite string under momentum of the wind velocity, when the disc assembly is released by the operator, the plate engaging the control elements of the latch to move the latch from the closed to the open position, thereby releasing the support section of the auxiliary retainer, the object gravitating toward the ground when released.
